Inventor:

W. W. Drummond

UNITED STATES PATENT OFFICE.

WILLIAM WHYTE DRUMMOND, OF LOUISVILLE, KENTUCKY.

DESIGN FOR A VENTILATOR OR AIR-GRATE.

SPECIFICATION forming part of Design No. 14,132, dated July 24, 1883.

Application filed June 1, 1883. Term of patent 7 years.

To all whom it may concern:

Be it known that I, WM. WHYTE DRUMMOND, a citizen of the United States, residing at Louisville, in the county of Jefferson and

5 State of Kentucky, have invented and produced a new and original Design for Ventilators, of which the following is a specification, reference being had to the accompanying drawings, forming part thereof.

10 Figure 1 is a front elevation of my newly-designed ventilator. Fig. 2 is a top view of the same, these two views being deemed necessary to fully illustrate my design.

The leading feature of my design consists in a series of circles, with a cross in the center of each circle, and all attached to an outside frame.

A represents the formation of the ventilator, and B represents the air-passages.

I claim—

20 The design for an ornamental ventilator, as herein shown and described.

WM. WHYTE DRUMMOND.
